(57) **CLAIM**

The ornamental design for a drawer organizer, as shown and described.

DESCRIPTION

FIG. 1 is a perspective view of drawer organizer showing my design.

FIG. 2 is a front view thereof;

FIG. 3 is a bottom view thereof;

FIG. 4 is a top view thereof;

FIG. 5 is a rear side view thereof;

FIG. 6 is a left side view thereof;

FIG. 7 is a right side view thereof; and,

FIG. 8 is an enlarged, fragmentary view of the mesh embodied in our new design.

The broken line around the edge of the fragmentary view of FIG. 8 is included for the purpose of showing an edge of the drawer organizer that forms no part of the claimed design.
